UNITED STATES PATENT OFFICE.

JOHN JAMES DILLON, OF SAULT STE. MARIE, ONTARIO, CANADA.

AUTOMATIC RAILWAY SWITCH STAND.

Application filed December 4, 1922. Serial No. 604,961.

To all whom it may concern:

Be it known that I, JOHN JAMES DILLON, a subject of the King of Great Britain, and a resident of the city of Sault Ste. Marie, in the Province of Ontario and Dominion of Canada, have invented certain new and useful Improvements in Automatic Railway Switch Stands, of which the following is a specification.

10 This invention relates to improvements in automatic railway switch stands, and the objects of the invention are to provide a simple and effective means which will permit the switch to be run through by cars or engines without turning the switch to take care of emergency cases where such are unavoidable.

Further objects are to render the switch inoperative after it has been run through until certain adjustments have been made, and to render these adjustments of such a character that they will entail sufficient trouble to deter trainmen as far as possible from running through the switches.

25 Further objects still are to provide a simple and effective means for adjusting the throw of the switch in order to keep the switch points at all times tight to the rail stock.

30 Further objects still are to provide simple and effective means for automatically locking the handle in down position each time the switch is operated.

Still further objects are generally to improve and simplify the construction of the device to better adapt it to perform the functions required of it.

And it consists essentially of the improved construction hereinafter described in detail in the accompanying specifications and drawings.

In the drawings:

Figure 1 is an elevation of an embodiment of the invention.

45 Figure 2 is a plan view.

Figure 3 is a sectional elevation.

Figure 4 is a section on the line 4—4 of Figure 3.

50 Figure 5 is a section on the line 5—5 of Figure 3.

Figure 6 is a sectional view on the line 6—6 of Figure 4.

In the drawings, like characters of reference indicate corresponding parts in all the figures.

Referring to the drawings:

A indicates the base casting constituting a casing and framework in which the mechanism works. B is the main shaft extending vertically through the casing having at its lower end the eye bolt or crank 11, connected by suitable mechanism to the switch-point in the usual way. C indicates the operating handle which is pivotally mounted in the rotatable head D, which latter is mounted with limited freedom of rotation on the table E and is formed with a recessed portion 12 in which the end of the handle C is pivoted.

To lock the handle in its down position, I provide a pivoted stop dog 13 mounted on a pin 14 which, on the outside of the head, is connected to a weighted handle 15 which is so positioned that it tends to hold the dog 13 in locking position. It will be seen that the dog 13 is formed with two stop lugs 16 and 17, the lug 17 abutting the side of the recessed portion 12, while the lug 16 in normal position is adapted to project in front of the end 18 of the lever C and thus prevent raising of the lever. When the handle 15, however, is swung over, the operating handle C will be clear of the dog 13.

The head D is mounted in its proper vertical position in ordinary circumstances by means of a nut 19 on a threaded portion 20 of the shaft B, the nut being protected from the weather by a sealing member or cup 21 mounted on a reduced and squared portion 22 of the shaft B and held in position by a suitable split pin 23. The head D is not directly connected to the shaft B but is connected thereto through spring clutch mechanism presently to be described.

This spring clutch mechanism includes an upper slip member F and a lower slip member G having interlocking faces or teeth 24 and 25, the faces or teeth being so shaped that, under excessive pressure, the members F and G may slip past each other while the member G is forced longitudinally downwardly. This forcing is resisted by means of a strong coil spring 26 which extends from the bottom of the slip member G to a washer 27 mounted above a two-part collar H.

This collar H is formed with a threaded lower portion 28 and a squared upper portion 29 which have a bent joint with each other, the collar itself resting on the bottom

plate 30 of the casing. The head D is connected to the member F by means which are released upon vertical movement of the head; these means comprising a ratchet-shaped extension 31 which fits a correspondingly shaped socket 32 on the head F, thereby constituting a clutch connection between the two.

In operation, when the handle C is swung, 10 the head D turns and with it the upper slip casting F. The latter operates and turns the lower slip casting G, which turns the main shaft by reason of the main shaft being formed with a squared portion 33 where it 15 passes through the lower slip casting G, the said casting being provided with a correspondingly shaped hole 34, while the hole 35 in the upper casting through which the shaft B extends is round. The turning of 20 the main shaft turns the crank 11, and thereby moves the switch-point in the usual way.

Where from emergency the switch is run through without turning of the handle and head D, the following occurs:—The crank 11 25 at the bottom of the shaft B is forced to turn by the cars running through and forcing the switch-point; the turning of this crank turns the main shaft B from top to bottom together with the lower slip casting 30 G, the upper slip casting remaining stationary, and the coil spring 26 being forced down allows the joint between the upper and lower slip castings to work and to turn the necessary one quarter of a circle.

This forcing of the switch operation renders it inoperative until proper adjustments are made, because the head D and the upper slip casting F are connected by the clutch joint, already described, and, furthermore, 40 the head D is so arranged that it may only turn one quarter of a revolution, this being accomplished by providing a stop lug 36 on the head which is limited in its movement by pins 37 and 38 on the table E (see Fig. 2).

The adjustment to render the switch operative again involves the raising of the adjusting nut 19 sufficiently to allow the clutch between the head D and the upper slip casting to be broken; in other words, to permit 50 the ratchet portion 31 to be withdrawn from the recess 32 when the head and handle may be turned one-quarter of a circle and the clutch reconnected, the nut being then screwed down and the adjustment completed.

55 The means which I provide for adjustment of the switch-points comprises a bolt 41

which extends through oblong holes 42 in spaced lugs 43 provided on the casing A, the bolt having intermediate of these lugs, screw-threaded engagement with a lug 44 provided on the table E, said table being connected to the casing by means of a lip 45 which engages a recess 46 in the casing.

It will be seen that adjustment of the bolt 41 will adjust the relative angular position of the table E and the casing, and so cause slight adjustment in the position of the main shaft and of the switch points.

As many changes could be made in the above construction and many apparently widely different embodiments of my invention within the scope of the claims, constructed without departing from the spirit or scope thereof, it is intended that all matter contained in the accompanying drawings 75 shall be interpreted as illustrative and not in a limiting sense.

What I claim as my invention is:

1. An automatic switch stand of the character described comprising a casing, a main operating shaft extending vertically in the casing, a top plate, a head rotatably mounted on the top plate, a handle connected to the head, a pair of slip clutch members having interlocking teeth, a clutch connection between one of the clutch members and the head, a non-rotatable connection between the other clutch member and the shaft, spring means for holding the clutch members in engagement with each other, said spring connection including a spiral spring and a collar surrounding the shaft and bearing on one side against the spring and on the other side against the casing, and a nut on the shaft bearing against the head member.

2. In a switch stand of the character described, a casing, spaced lugs on the casing, a top plate having a lug extending between the said spaced lugs, adjusting means extending between the said lugs whereby the position of the plate may be adjusted with respect to that of the casing, an operating head on the plate, a main shaft connected operatively to the head, and an operating handle on the head.

In witness whereof I have hereunto set my hand in the presence of two witnesses.

JOHN JAMES DILLON.

Witnesses:

EDWARD ROSS MACKAY,
HENRY SIDNEY HAMILTON.
